UNITED STATES PATENT OFFICE.

JOHN W. KITTREDGE, OF AKRON, OHIO.

HOIST.

1,318,568.

Specification of Letters Patent. Patented Oct. 14, 1919.

Application filed December 15, 1915. Serial No. 66,996.

To all whom it may concern:

Be it known that I, JOHN W. KITTREDGE, a citizen of the United States, residing at Akron, in the county of Summit and State 5 of Ohio, have invented a new and useful Hoist, of which the following is a full, clear, and exact description.

My invention relates to hoists in which an electric motor operates a winding drum, 10 and is applicable to derricks, cranes, mines, elevators and the like.

The objects of my improvements are;— 1st. To provide a hoist of small first cost, size and weight.

15 2nd. To make it simple, working with few operations on the part of the operator, thus economizing labor, time and skill.

3rd. To eliminate the wearing parts and thus reduce the friction.

20 4th. To provide an automatic stop and prevent accidentally hoisting the load into the overhead sheave.

I attain these objects by the mechanism shown in the accompanying drawings, in 25 which;

Figure 1 is a longitudinal cross-section; Fig. 2 is an end view; Fig. 3 is a fragmentary side elevation with the upper half in section.

30 A given piece carries the same number throughout the several views. For convenience of description, parts fastened rigidly together are cross-hatched alike, though they may be different pieces of 35 metal. In such a case the whole part, moving as a single piece, is designated by a single numeral, as 8, and different ends or faces by that numeral with letters as 8^A, 8^B, 8^C, etc.

40 The machine consists of a base 1, supporting housings with bearings 2 and 3. Bearings 2 and 3 carry the rotating armature of a motor 5, similar in function to the starter of an ordinary motor but differing in 45 form, and the rotating armature 5 carries the rotating field 6, and the shaft 6^B, which are entirely similar to the corresponding parts of commercial motors. The rotating armature 5 may rotate in its bearings 2 and 3 and its periphery is in the form of a drum 5^A, and winds the hoisting rope 7. Electric current is brought to the rotating armature by the collecting rings 5^C and the brushes 3^A held in the support 3^B. The collecting 55 rings are insulated by the insulator 5^D.

On its outer end, the rotating armature 5 carries an annular gear 5^B. The shaft 6^B carries a pinion 8^A turning loosely on the shaft. A clutch, hereinafter described, 60 grips it to the shaft at the will of the operator. The pinion 8^A has a sleeve 8^B, and on this sleeve is mounted a second annular gear 9. Mounted on the shaft 6^B and the sleeve 8^B, are two disks 10^A and 10^B, carrying the shafts 10^C and 10^D, and on these two shafts 65 are mounted two double gears 11 and 12. The disks 10^A and 10^B are bolted to the filler plates 10^F shown dotted in Fig. 2, which binds the disks rigidly together without interfering with the gears. The gears 70 11^B and 12^B mesh with the pinion 8^A and also with the annular gear 9, forming a set of planetary gears, shown by their respective pitch circles in Fig. 2. The gears 11^A and 12^A mesh with the annular gear 5^B. The 75 ratio of 5^B to 11^A or 12^A is slightly different from the ratio of 9 to 11^B or 12^B. Thus as the gears 11 and 12 are rotated, a slight difference in the speed of rotation is transmitted to the annular gears 5^B and 9. 80

To illustrate:—Suppose the pinion 8^A to have 24 teeth; gears 11^B and 12^B to have 62 teeth each; gears 11^A and 12^A to have 21 teeth each; and annular gears 9 and 5^B to have 148 and 107 teeth respectively. Suppose the annular gear 5^B is made stationary for the time being, as by having the rope 7 fastened to a heavy weight 15, and suppose the pinion 8^A to revolve counter clockwise, as indicated by the arrow. The disks 10^A 90 and 10^B revolve in the same direction as the pinion but more slowly, and the double gears 11 and 12 move about the central shaft 6^B and also turn on their own axles 10^C and 10^D. Gear 9 moves slowly clockwise. 95

Now suppose the annular gear 9 is brought to rest by a brake. The proper brake for this purpose is not a part of this invention and for purposes of this patent application a simple band brake 13 and 100 pedal 14 are shown. The pinion 8^A and gears 11 and 12 rotate almost as before, and the annular gear 5^B revolves slowly counter clockwise or in the same direction as the pinion 8^A and raises the weight. With gears 105 as above described, the pinion 8^A running 1150 R. P. M. turns the gear 5^B and the drum 85 R. P. M., and with a pitch diameter of 27 ins. for the winding drum, gives a hoisting speed of 600 feet per minute. 110

Now suppose the brake 13 is released allowing the drum to unwind and the weight 15 to drop. Both annular gears 5^B and 9 now turn nearly together and carry the train 5 of gears around with them. It will be noted that when the rotating field and the rotating armature are connected by the train of gears, they have a definite speed relation, but with the brake released, there is no mechanical 10 connection and an electrical relation only.

The pinion 8^A was said above to be loose on the shaft 6^B. It is connected to it by a cone clutch, 16 which moves longitudinally on the shaft 6^B but is held to the same 15 rotation as the shaft by the feather key 6^C. The clutch 16 engages a cone 8^C which is rigid with the pinion 8^A. The clutch 16 is held in contact with the cone 8^C by a spring 18. The outer periphery of annular gear 20 has a screw thread 5^C and operates a rack 20. The rack 20 passes through a hole in the lever 19 and, as the drum hoists, the screw thread 5^C moves the rack 20 toward the lever 19. The rack 20 is itself threaded and 25 carries a wing nut 21. When the load 15 has reached a certain predetermined height, the nut 21 comes in contact with the lever 19 and as the rack 20 continues to move, compresses the spring 18 and forces the cone 30 clutch 16 out of contact with the cone 8^C. Owing to the difference in the length of the lever arms, it disengages quickly. The piece 8 has a slight longitudinal movement along the shaft 6^B. It has a conical shoulder 8^D 35 which may engage a concave cone 10^B in the disk 10^B. The spring 22, which is a weaker spring than the spring 18, bears against piece 8. When both springs are free to act, the spring 18 compresses the spring 40 22, forces the cones 16 and 8^C into contact and forces the cones 8^D and 10^B out of contact, and this connects the rotating field 6 to the gear train. When the spring 18 is compressed and the clutch 16 disengaged by the 45 lever 19, then the spring 22 forces the cones 8^D and 10^B into contact. Disengaging the cones 16 and 8^C disconnects the gears from the rotating shaft and engaging the cone 8^D with the cone 10^B binds the gears together 50 and is a brake.

Suppose the hoist is used for lifting buckets of earth to build a grade. The operator lifts the bucket by setting the band brake 13. When the bucket is slightly higher than the 55 grade, the wing nut 21 disengages the gears from the source of power as just described, and the cone brake 10^B holds the gears while both brakes are set, the bucket remains at the given height until it is moved over the 60 grade and dumped. The means for moving it horizontally and dumping are not essential to this invention. To lower the bucket for refilling, the operator simply releases the band brake 13. The moment the screw 65 thread 5^C turns in the direction of lowering,

it disengages the wing nut 21 from the lever 19, disengages the cone-brake 10^B and sets the cone clutch 16 ready to lift another bucketful. Thus the operator lifts the bucket, holds it stationary, lowers it, and 70 controls the speed of the lowering by two operations, only, the setting and releasing of the band-brake 13. This effects a considerable saving of time and labor over a hoist that has the brake and the connection to the 75 power in separate mechanisms, controlled by separate levers, or one in which it is necessary to throw off the power before shifting from one mechanism to the other. As the height of the grade increases from the consecutive bucketsful of earth, the bucket can be stopped at a greater height by simply 80 screwing the wing nut 21 a slight distance along the rack 20.

If the thread 5^C is an inch pitch and the 85 drum circumference is 7 feet, then moving the wing nut 21 an inch along the rack 20 changes the height of the stop 7 feet. It will be observed that the stop is a given distance from the machine, not from the point of 90 loading. The consecutive bucketsful can be loaded at different levels, but under the action of the wing nut 21 will stop at the same level.

The spring 18 is held in place by a wing 95 nut 23, on a threaded portion of the shaft 6^B. When it is necessary to hoist consecutive loads to different heights, the wing nut 23 is screwed back, rendering the spring 18 inoperative and the wing nut 21 is screwed 100 back entirely away from the lever 19. This sets the brake 10^B and disconnects from the power. By the hand lever 19, the operator can then throw on the power and release the 105 brake 10^B at will, and vice versa.

This is a general description of my invention. The figures for gears, speeds, etc., are, of course, for illustration only, as the design is adaptable to many speed reductions and other modifications.

By reversing the cable and band 13, the machine may be made to lower when the drum is running in the same direction as the rotating field, and to hoist when running in the opposite direction.

These and other modifications are within the spirit of this invention.

Having thus described my invention, I claim as new and desire to secure by Letters Patent—

1. A drive shaft, a winding drum, a cable on said winding drum, a planetary gear connection from the drive shaft to the winding drum, a clutch actuating and releasing a member of the said planetary gear connection, a brake controlled by the operator adapted to permit, to retard or to stop the backward rotation of the drum, frictional means adapted to automatically bind the mechanism against backward rotation when 120 125 130

the brake is engaged and the clutch is released and adapted to automatically release the mechanism when the clutch is engaged.

2. A drive shaft, a winding drum, a cable 5 on the said winding drum, a planetary gear train from the drive shaft to the winding drum, a clutch engaging and releasing a member of the said planetary gear train, a friction brake, a connection from the said 10 friction brake to the drum, a connection from the said friction brake to the clutch, the connection being such that the friction brake automatically engages when the clutch releases and automatically releases when the 15 clutch engages, and frictional means manually controlled adapted to permit, to retard or to stop the backward rotation of the drum.

3. A drive shaft, a winding drum, a cable 20 on the said winding drum, a planetary gear train from the drive shaft to the winding drum, a clutch in the said planetary gear train, brake control of the said drum automatically operated, the arrangement being 25 such that the brake sets automatically when the clutch releases and that the brake releases automatically when the clutch engages, and brake control of the said drum controlled by the operator.

30 4. A drive shaft, a winding drum, a cable on the said winding drum, a planetary gear train from the drive shaft to the winding drum, a brake controlled by the operator adapted to permit, to retard or to prevent 35 the backward rotation of the drum, frictional means engaging and releasing a member of the planetary gear train, and thereby, when the man-operated brake is set, actuating and releasing the said drum, and a brake 40 operated automatically, the arrangement being such that it engages automatically when the said frictional means release the said member of the planetary gear train and that it releases automatically when the said frictional means engage the said member of the 45 planetary gear train.

5. A drive shaft, a winding drum, a cable 50 on the said winding drum, a planetary gear train from the drive shaft to the winding drum, a clutch engaging and releasing a member of the planetary gear train, a brake controlled by the operator, a connection from the brake to the drum, the said brake adapted to hold or retard the drum against 55 backward rotation, a second brake automatically controlled, a connection from the second brake to the drum, a connection from the second brake to the clutch, the connection being such that the second brake automatically 60 binds the drum against backward rotation when the first brake is set and the clutch is released and automatically releases the drum when the clutch is engaged, an automatic stop adapted to disengage the clutch

and an adjustment on the said stop whereby 65 it can be set to disengage the clutch at different predetermined positions of the cable.

6. A drive shaft, a winding drum, a rope or cable on said winding drum, a gear train, 70 said gear train connecting the drive shaft to the winding drum, a brake, said brake engaging and releasing a member of the gear train, a clutch, said clutch engaging and releasing another member of the gear train, the brake adapted to connect and disconnect 75 the drive shaft from the winding drum when the clutch is engaged, the clutch adapted to connect and disconnect the drive shaft from the winding drum when the brake is engaged, the brake also adapted to hold or retard 80 the drum against backward movement when the clutch is released, another brake, said second brake automatically engaging a member of the gear train when the clutch is released and automatically releasing said 85 member of the gear train when the clutch is engaged.

7. A drive shaft, a winding drum, a cable on said winding drum, a gear connection 90 from the drive shaft to the winding drum, said gear connection comprised of a set of planetary gears with carrier adapted to carry the planet gears around the central pinion, a band brake, said band brake engaging and releasing a member of said gear connection, 95 a clutch, said clutch engaging and releasing another member of said gear connection, the band brake adapted to connect and disconnect the drive shaft from the winding drum when the clutch is engaged, the clutch adapted 100 to connect and disconnect the drive shaft from the winding drum when the band brake is engaged, frictional means adapted to automatically engage one of the said gears with the carrier when the clutch is released and 105 means for automatically releasing the said gear from the carrier when the clutch is engaged.

8. A drive shaft, a winding drum, a cable on said winding drum, a gear train from 110 the drive shaft to the winding drum, a brake retarding and releasing a member of the gear train, a clutch actuating and releasing another member of the gear train, the brake adapted to connect and disconnect 115 the drive shaft from the winding drum when the clutch is engaged, the clutch adapted to connect and disconnect the drive shaft from the winding drum when the brake is engaged, the brake also adapted to hold or retard the drum against backward movement when the clutch is released, a second brake adapted to automatically hold a gear of the train against backward movement when the clutch is released and adapted to automatically release said gear when the clutch is engaged, an automatic stop adapted to disengage the clutch, and an adjustment on said 120 125

4
stop whereby it can be set to disengage the clutch at different predetermined positions of the cable.

9. An electric motor comprised of an inner 5 and an outer member, trunnions on said outer member and the said outer member revolute thereon, bearings and the said trunnions supported therein, a drive shaft and the said inner member supported thereon and rigid 10 therewith, bearings within the trunnions of the outer member and concentric therewith, the said drive shaft journaled in the said bearings in the trunnions of the outer member and revolute therein, a 15 winding drum, the said winding drum around the periphery of the outer member of the motor and integral therewith, a mechanical power transmission and the said power transmission connecting the said drive shaft 20 to the said winding drum, a brake engaging

and releasing one member of said power transmission, the arrangement being such that when it is engaged, power can be transmitted through its engaging member and when it is released, power cannot be so transmitted, a clutch in said power transmission, 25 a second brake, said second brake automatically engaging a member of the power transmission when the clutch is released and releasing said member when the clutch is engaged. 30

In testimony whereof, I have signed my name to this specification in the presence of two subscribing witnesses this 11th day of December, A. D. 1915.

JOHN W. KITTREDGE.
